[57] ABSTRACT

[21] Appl. No.: 492,886

A weight increasing device adapted to be mounted on an ice skate between the two posts supporting the boot of the ice skate. The device fits tightly between the two posts and abuts against each other. The device comprises a block which constitutes the mass of the device and a leg which projects outside said mass and is spring mounted so as to exert a longitudinal tension between the two posts.

SHEET 1 OF 2

FIG. 1

FIG. 2

WEIGHT INCREASING DEVICE FOR SKATE

The present invention relates to a weight increasing device adapted to be mounted on an ice skate and in particular between the two posts supporting the boot on the blade.

Exercising weights for ice skates have already been used according to the U.S. Pat. No. 3,582,067.

The purpose of mounting additional weights on ice skates is to increase the muscular and control of the hockey players, professional or ordinary skaters who intend to improve their performances and resistance at skating. Although general physical exercise has been recognized as valuable for practising a specific sport, it is preferable to exercise the specific muscles which are most commonly used for that specific sport.

It is the main object of the present invention to attach a weight to a skate in order to require a greater performance from the legs of the skaters within a shorter period of time.

It is another object of the present invention to solidly secure the weights to the skates so as to make sure that they will not move during any regular exercise of the skater.

Still another object of the invention is to provide a securing means which will make the device easily installed or removed from the ice skates so that a skater may install or remove it quickly before a hockey game, an artistic performance or a mere exercise practice.

The present invention is more specifically directed to a weight increasing device adapted to be mounted on an ice skate having a boot, a blade and a pair of posts for supporting the boot on the blade, the device being adapted to be mounted between the said two posts, the said device comprising a relatively heavy mass, means fixed to said mass for gripping said posts, means for varying the longitudinal length of the device and means for fixing the length of the device at a predetermined length.

The proposed device preferably uses a spring-loaded weight constructed so as to abut against each post and be locked tightly so as to be rigidly secured thereto.

The present invention will now be described in greater details by referring to the drawings, wherein:

FIG. 1 is a side view of a spring-loaded weight mounted between the posts of an ice skate,

FIG. 2 is a perspective view of one embodiment of the weight increasing device according to the invention,

FIG. 3 is a top view of the spring-loaded weight shown in FIG. 1,

FIG. 4 is a top view of another embodiment of a spring-loaded weight for skates,

FIG. 5 is a top view of an alternative embodiment thereof, and

FIG. 6 is a top view of a different embodiment of the weight increasing device for skates.

As shown in FIGS. 1, 2 and 3, a weight increasing device 10 is mounted between posts 12 and 14 of the skate boot 16 having the blade 18. The weight increasing device 10, in FIG. 1 corresponds to the device 10 in FIGS. 2 and 3 and consists of a block member 20 which has a parallelepipedic shape with a concave recessed end 22. The other end of the block member 20 has a cylindrical hollow portion through which is inserted the rod 24 projecting outside the block member and at the outer end of which is rigidly secured a con-

cave shoulder 26. The curvatures of the concave recess 22 and the concave shoulder 26 respectively correspond to the curvatures of the posts 12 and 14. The rod 24 has a flat recessed surface 28 so as to prevent it from sliding outside the block member 20 on account of the pin 30 which transversely projects through the member 20 and in line with the recessed surface 28. Accordingly, the rod 24 has a sliding length corresponding to the length of the flat recess surface 28. A coil spring 32 is axially mounted over the rod 24 and extends between the shoulder 26 and a cylindrical recess 34 in the block member 20. This spring urges the rod 24 outwardly of the member 20 until the pin 30 hits the protuberance 36 at the end of the rod 24.

15 The device 10 is contracted when inserted between the posts 12 and 14 and takes its normal dimension according to the distance between the posts 12 and 14. In order to prevent an unintentional release of the device between the posts when the skater performs his skill, a 20 wing-screw 38 is transversely threaded through the block 20 and tightens against the rod 24. In this position, the skater can safely move about the ice without being afraid for the device to loosen and especially to hurt someone on the ice.

25 Considering that the walls of the posts 12 and 14 of ordinary ice skates are at an angle from each other, it is important that the device be oriented so as to take up the longest distance between the two posts 12 and 14. One of the solutions for this problem is to angularly dispose the device along the axis corresponding to the longest distance between the inner walls of the posts 12 and 14 as shown in FIG. 1.

Another embodiment is illustrated in FIG. 4 and consists of two block members 40 and 42 respectively having at their outer end and a recessed groove 44 and 46 for abutting against the skate posts. A pin 48 is mounted between the two blocks and projects inside a hollow portion inside each of them. The pin has a protuberance 50 and 52 at each end and is prevented from sliding out by a pin 54 and 56 aligned with the recessed surfaces 53 and 55 on the side thereof. Wing-screws 58 and 60 are mounted through each block to lock the pin 48 in position when the distance between the blocks 40 and 42 is determined or reached. The spring 62 is axially mounted over the pin 48 and abuts at each end in cylindrical recesses 64 and 66. Accordingly, the two blocks 40 and 42 will have the tendency to be spaced from each other but be prevented from falling off the pin 48 due to the pins 54 and 56 abutting against the protuberances 50 and 52.

50 The device is similarly used as the one illustrated in FIG. 1 so that when the device is inserted between the two posts of the skates, the blocks are locked in position by the screws 58 and 60. If the device is intended to be angularly oriented between the two posts, the curves of recesses 44 and 46 will have to be shaped accordingly as illustrated by the slope 45.

Another embodiment of the invention is illustrated in FIG. 5 and consists of the block member 70 at both ends of which are mounted hook members 72 and 74 which are intended to grip the posts of the skate. The hook 72 is solidly secured to the block 70 and the hook member 74 has a leg 75 which penetrates a cylindrical recess 76 in the block member 70. A coil spring 73 is mounted around the portion of the leg 75 outside the block member 70 and is fastened at each end to a hole 71 in the hook member 74 and to a loop 77 fixed to the

block 70 adjacent the outlet of the hollow portion 76. A wing-screw 78 is transversely mounted through the block 70 so as to tighten the leg 75 in a predetermined or reached position through the block 70.

The operation of the device shown in FIG. 4 is obtained by hooking the two hooks 72 and 74 to the posts of the skate and by tightening the screw 78. It is obvious that the two hook members 72 and 74 must grip sufficiently around the posts of the skates so as to prevent their unintentional releasing from the posts.

A further embodiment is illustrated in FIG. 6 which comprises two block members 80 and 82 having at each outer end a recessed groove 81 and 83 adapted to fit unto the posts of the skate. The two block members 80 and 82 are connected to each other by a threaded rod 84 which is adapted to laterally vary the distance between them. The rod 84 has a left-hand thread 86 mounted through the block 80 and a right-hand thread 88 mounted through the block 82. When the knob 90 is rotated, the blocks 80 and 82 can simultaneously move apart or towards each other so as to adjust to the right dimension. When both blocks 80 and 82 abut against the lateral wall of the posts of the skate, the relative motion between the rod 84 and the blocks 80 and 82 is locked by the wing-screws 92 and 94. Each grooved surface 81 and 83 may be appropriately slanted as shown by the slope 85.

An additional means for securing each end of the device to the posts is by providing magnetic elements at each end of the device.

Furthermore, in order to prevent the vertical movement of the weight increasing device, it is possible to foresee the thickness of the blocks described above to a dimension corresponding to the distance between the sole of the boot and the upper surface of the blade.

It is also within the embodiment of the invention to use magnetic elements in combination with the upper surface of the blocks so as to magnetically contact the metallic plates on the under sole of the boots.

In the embodiments described above, it is preferred to locate the wing-screws on the outer side of the device so that the head of two adjacent devices in a skat-

er's foot would not touch each other.

What I claim is:

1. A weight increasing device adapted to be mounted on an ice skate having a boot, a blade and a pair of posts for supporting the boot on the blade, the said device comprising a weighted block member, a rod slidably mounted in said block member and extending outside therefrom, spring means mounted between the block member and the rod for resiliently biasing said rod-relative to said block member and means for positively retaining the rod to said block member to prevent it from sliding completely out therefrom, and gripping means disposed at the free end of the rod and at the end of the block member opposite the rod for laterally retaining the said device to said posts.

2. A device as recited in claim 1, wherein the said spring means is a coil spring concentrically disposed over the said rod and adapted to abut against the block member and the gripping means located at the free end of the rod.

3. A device as recited in claim 2, wherein the said rod has a flattened surface along a portion of one side of its periphery to form a recessed surface thereon, the said rod retaining means comprises a pin transversely fixed through the block member and aligned with said recessed surface so as to limit the longitudinal displacement of said pin.

4. A device as recited in claim 3, wherein a shoulder member is secured at the free end of the said rod, the gripping means are essentially constituted of a recessed groove provided in said shoulder member and the block member, the angle of the axis of each of said grooves corresponding essentially to the angle of the periphery of the post on which it is adapted to abut.

5. A device as recited in claim 4, comprising a threaded screw transversely mounted in said block member and adapted to abut against the said rod, whereby the said rod is adapted to be releasably locked in a fixed longitudinal position.

6. A device as recited in claim 3, wherein the gripping means comprises hooks at each end of said device.
